Albert E. Hall, 8885 Halvorson Drive, Elk Grove, Calif. 95624, and Benjamin A. Thompson, P.O. Box 864, Walnut Grove, Calif. 95690

Filed July 28, 1971, Ser. No. 167,062

Term of patent 14 years

Int. Cl. D8—08

U.S. Cl. D8—229

FIG. 1.

FIG. 2.

FIG. 3.

FIG. 4.

FIG. 1 is a front elevational view of a rope fastener showing our new design;

FIG. 2 is a side elevational view, the top plan view and the bottom plan view being substantially identical thereto owing to the radial symmetry of the design;

FIG. 3 is a rear elevational view; and

FIG. 4 is a median, vertical, sectional view, the plane of the section being indicated by the line 4—4 in FIG. 3.

We claim:

The ornamental design for a rope fastener, as shown and described.
